UNITED STATES PATENT OFFICE.

EBEN CAVENDER, OF PHILADELPHIA, PENNSYLVANIA.

CLOTHES-WASHING ATTACHMENT FOR SET TUBS.

1,080,324.

Specification of Letters Patent.

Patented Dec. 2, 1913.

Application filed September 2, 1911. Serial No. 647,322.

To all whom it may concern:

Be it known that I, EBEN CAVENDER, a citizen of the United States, residing at the city of Philadelphia, in the county of Philadelphia and State of Pennsylvania, have invented a certain new and useful Clothes-Washing Attachment for Set Tubs, of which the following is a specification.

The principal objects of the present invention are to provide a washing machine attachment which can be readily connected and disconnected with an ordinary set washing tub such as is usually installed in dwellings and which is firmly and properly held therein for use; to provide for properly securing the fixed part of a washing machine in place in an ordinary set tub; and to provide a convenient, comparatively inexpensive and efficient machine for satisfactorily washing clothes in a set tub thereby obtaining the advantage of hot and cold water and drainage.

The invention will be claimed at the end hereof but will first be described in connection with the embodiment of it chosen from among various embodiments for illustration in the accompanying drawings in which—

Figure 1, is a front view, partly in elevation but principally in section, illustrating a clothes washing attachment embodying features of the invention in application to a set tub. Fig. 2, is a sectional view partly in section of the same, and Fig. 3, is a view illustrating a detail of construction.

In the drawings there is a base comprising a member 1, having at each end a pair of rigid arms 2 and 3, fitted at their ends with clamps 4, and whereof only the arms 2, are upright and the arms 3, are inclined in respect to the member 1. The member 1, is arranged at the bottom of the tub 5. The clamping members of the arms 2, engage the top edges of the end walls 6, of the tub and the clamping devices of the arms 3, engage the top edge of the front wall 7, of the tub. There is a swinging frame pivotally connected as at 8, at or near one of its edges with the base, and this frame consists of end pieces 9, shown as of inverted T-shape and of a rail 10, connecting the heads of the end pieces and rails or strips 11 and 12, connecting the ends of the arms of the end pieces. This structure constitutes a dasher. The rail

12, is shown as of the form of an inverted trough and is detachably connected with the end pieces, for example, by means of a pin and slot 13, and a catch 14. The catch consists of a bolt attached, so as to be movable, to the part 12, and this bolt is adapted to engage and disengage a keeper attached to the part 9. The bolt overlies the pin on the part 12, so that when the bolt is free from its keeper the pin can be lifted out of the slot in the part 9. The part 12, can therefore readily be removed for the purpose of putting in or taking out clothes.

15, is a handle by means of which the dasher can be operated back and forth and this handle is shown as working in a slot in the cover or lid 16. The clamping devices 4, 70 may be adjustably connected with their arms by means of a slot and set screws 17, as shown in Fig. 3. The rails 11, are shown as of trough-like section.

In use the arms 2 and 3, by engaging the top edges of the side walls 6, and the top edge of the front wall 7, hold the base firmly in proper position in the tub, and the dasher with its various trough-shape rails and flat rail 10, when swung back and forth efficiently washes the clothes. The water and drainage connections of the set tub make a washing operation easy and convenient and the device can be applied to any ordinary set tub and successfully held therein for 85 operation.

What I claim is:

A clothes washing attachment for set tubs comprising arms constituting a fixed frame and extending from the bottom of the tub 90 and terminating at the top edge of the tub and whereof some clamp the front wall and some the end walls of the tub, in combination with a single swinging frame consisting of end pieces and rails and provided at its top 95 edge with an upwardly extending handle, and a pivotal connection arranged at the bottom of the tub and connecting the fixed frame and the lower edge of the swinging frame, substantially as described.

In testimony whereof I have hereunto signed my name.

EBEN CAVENDER.

In the presence of—

CLIFFORD K. CASSEL,
K. M. GILLIGAN.
